UNITED STATES PATENT OFFICE.

SAMUEL JAMES TRITT, OF CARLISLE, PENNSYLVANIA.

ELEVATOR.

1,426,524.

Specification of Letters Patent. Patented Aug. 22, 1922.

Application filed September 22, 1919. Serial No. 325,358.

To all whom it may concern:

Be it known that I, SAMUEL JAMES TRITT, a citizen of the United States, residing at Carlisle, in the county of Cumberland and State of Pennsylvania, have invented certain new and useful Improvements in Elevators, of which the following is a specification.

This invention relates to elevators, and more particularly to elevators designed for the purpose of carrying corn stalks, fodder, or the like materials up into a bin, silo, or other suitable receptacle.

The general object of this invention is to provide a very simple and readily adjusted elevator of this character which may be readily engaged with or disengaged from the bin or like structure in which the material is to be discharged and which may be adjusted to discharge the material into different parts of the bin or silo.

A further object is to provide an elevator of this character so constructed that the carriers will occupy the least possible space when descending after discharging the material therefrom so that the elevator may be compact in form and disposed close to a silo, bin, or other structure.

Other objects will appear in the course of the following description.

My invention is illustrated in the accompanying drawings, wherein:—

Figure 1 is a fragmentary view in side elevation illustrating an elevator constructed in accordance with an embodiment of my invention.

Figure 2 is a view in front elevation of the structure illustrated in Figure 1 with certain of the parts shown in Figure 1 omitted.

Figure 3 is an enlarged horizontal sectional view taken through the lower portion of the structure as illustrated in Figures 1 and 2.

Figure 4 is a fragmentary vertical sectional view taken through the structure as illustrated in Figure 3, and

Figure 5 is a fragmentary view in top plan illustrating the means for maintaining the device in desired lateral adjustment.

Figure 6 is a fragmentary elevation of the hangers 9 and the supporting wheels 11^a and allied parts, the sprocket chains 12 being in section.

As disclosed in the accompanying drawings, my improved elevator includes two

substantially parallel side members 1, which, when in working position, are substantially vertically disposed. The lower ends of the members 1 rotatably support a transversely disposed shaft 2 extending outwardly beyond each of the members 1, and to each extended portion of the shaft 2 is fixed a sprocket wheel 3. Each of the sprocket wheels 3 has disposed therearound a chain 4 in driven connection with a drive shaft 5 rotated in any desired manner, preferably through the instrumentality of a motor.

The upper end portions of the side members 1 rotatably support a second transverse shaft 6, and pivotally engaged with said shaft 6 adjacent to members 1 are the horizontally disposed members 7 of desired length. Each of the members 7 is held against swinging movement by a brace 7' connecting said member 7 and the adjacent side member 1. By lengthening or shortening the brace member 7' each of the side members 7 may be readily and conveniently adjusted with respect to the coacting side member 1, and as the occasions of practice may require. The outer or free end portions of the member 7 rotatably support a third transversely disposed shaft 8, and the inner end portions of said member 7 have depending therefrom the substantially transversely aligned arms or brackets 9, which rotatably support transversely extending, inwardly projecting stub shafts 10 (see Figure 6) which support the sprocket wheels 11^a.

The shafts 2, 6, and 8 have affixed thereto adjacent their opposite ends but inwardly of the members 1, the sprocket wheels 11, with which coact the endless chains 12, the direction of rotation of the shaft 5 being such as to cause the outer stretches of said chains to travel upwardly.

Mounted upon the chains 12 in predetermined spaced relation are the carriers B. Each carrier has substantially triangular end members. Each of these end members includes an upper, outwardly projecting bar 14 and a lower, upwardly projecting supporting bar 14^a on each side of the carrier, the two bars 14 and 14^a forming each end of the carrier converging at their outer ends and being rigidly connected to each other. Each pair of bars is engaged by a brace 17. The upper bars 14 of the end members of the bucket are pivoted to a transverse rod 15 which engages the two parallel

chains 12, while the lower bars 14^a are connected by means of a transverse rod 16 which, on the upward flight of the carrier, bears against that portion of the chain below the transverse pivot member 15. The lower bars 14^a are connected by means of a transverse brace bar 19. It will be seen that each carrier B is pivotally connected to the chains 12 at its upper inner corner by means 10 of a transverse rod 15. Extending from the transverse rod 15 are a plurality of tines 18 (see Figure 3) which are disposed in the same plane and in parallel relation to the bars 14.

15 Upon the upward movement of the chain, as upon the outer flight thereof, the bars 14 are supported in an upwardly and outwardly inclined position by means of the bars 14^a whose transverse rods 16 bear against the chain, as illustrated most clearly in Figure 1 and in Figure 4. Thus the tines 18 and the members 14 extend upwardly and outwardly in position to support a load and carry the load upward as the chains move 25 upward. Those links of the chains 12 immediately adjacent the cross rod 15 of each of the carriers and disposed above the carriers when the buckets are moving upwardly are pivotally connected by transversely disposed rods 15'. These rods provide a back for the carrier which prevents the load from spilling out as a carrier moves upward or when the carrier moves horizontally after it has reached the upper end of the elevator. 30 35 The carriers are supported in an upwardly and outwardly projected position as they move upward and as they move horizontally along the upper flight of the endless chains and after a carrier passes the wheels 11 on the outer ends of the arms 7 the carriers are still held in an outwardly projecting position but extending inward toward the downwardly moving flight of the chain. After the chains have passed the wheels 11, however, the carriers take the position shown in 40 Figure 1 and in Figure 4, that is they hang straight downward or as nearly straight downward as it is possible for them to hang and contact with the chains 12. It will be 45 obvious that as the carriers move upward they will carry up the material to be elevated and carry the material inward to a position above the storage bin, silo or other receptacle, whose breast or sill of the door opening is designated 24, and that as the carriers pass around the wheels 11 and the outer ends 50 of the arms 7, the material will be discharged into the bin, silo or other receptacle. 55

For the purpose of supporting the elevator in proper position on the receptacle and permitting the elevator to be turned in a horizontal plane, the upper end portions of the members 1 have engaged therewith the rearwardly directed beams 20, whose outer 60 ends are connected by a transverse beam 21.

Extending from the transverse beam 21 is a beam or arm 22, which carries a downwardly extending pin 26 disposed in the socket 25 formed in a plate 23 resting upon the upper face of the sill or breast 24 of 70 the storage receptacle. This pin 26 carries an arm 27 and the inner edge of the plate 23 is upwardly flanged and formed with teeth 28 with which the arm 27 is adapted to be engaged. Thus it will be seen that the 75 beam 22 and, therefore, the elevator may be oscillated around the pivot pin 26 and thus the elevator may be directed to discharge at different points of the receptacle.

The beams 1 and 7 are each provided with 80 the side plates 29, between which the carriers B travel. The adjacent ends of the plates 29 of the beams 1 and 7 are provided with the overlapping corner plates 30, so that said plates 29 of the members 1 and 7 85 will be substantially in continuity irrespective of the adjustment of the members 7 with respect to the members 1.

H denotes a feeding or delivery hopper 90 for coaction with the elevator, and this hopper has its bottom 31 inclined toward the delivery or discharge opening 32 arranged in the lower portion of the front wall 33 of the hopper. The opening 32 is of a width substantially equal to the space between the 95 side plates 29. The bottom 31 of the hopper H below the opening 32 is provided with the outstanding and substantially horizontally disposed spaced fingers 34, which extend between the side plates 29 and between which the tines or arms 18 of the carriers B travel upon the upward movement of 100 said carriers. The corn stalks or other material to be elevated, are deposited in the hopper H and pass by gravity out through the 105 opening 32 onto the fingers 34, and as the carriers B pass upwardly, they receive their load from the fingers 34.

It will be seen that this elevator is relatively light, that it may be easily handled 110 and put in place through the filling opening of a silo or over the top of a bin or through an air opening in a barn or other storage place and that when in place it is an easy matter to shift the elevator upon its 115 pivot 26 so as to cause the material to be discharged evenly within the silo, barn or other receptacle. It is to be particularly noted that because of the fact that the carriers B depend, as shown in Figure 1, approximately 120 parallel to the direction of movement of the flight to which they are attached, that the elevator may be placed very closely adjacent the wall of a storage bin or other receptacle, barn or the like so as to cause the apparatus 125 to take up but relatively little room outside of the receptacle.

I claim:

1. An elevator of the character described comprising an angular supporting frame 130

having a vertical portion and a horizontal portion, a pair of sprocket wheels disposed at the lower end of the vertical portion, a pair of sprocket wheels disposed at the upper end of the vertical portion, a pair of sprocket wheels disposed at the outer end of the horizontal portion, oppositely disposed sprocket wheels mounted upon the frame inward of and below the upper sprocket wheel, 5 a pair of connected sprocket chains passing around the first three pairs of sprocket wheels and over the last named pair of sprocket wheels, cross bars connecting said sprocket chains at intervals, carriers pivotally mounted upon said cross bars and including supporting bars mounted on the outer end of each carrier and extending at an acute angle thereto and abutting against the sprocket chains, said supporting bars 10 bearing against the chains and supporting the bodies of the carriers at an upward inclination as the carriers move upward and being longer than the bodies of the carriers whereby to support the carriers at an acute 15 angle to the chains, rods extending transversely of and carried by the chains and disposed at close intervals behind said carriers to form a back therefor, side plates attached to the vertical and horizontal portions of the frame and between which side plates the carriers move upward and outward, corner plates disposed at the junction of the horizontal and vertical plates, and 20 means for driving the lowermost sprocket wheel to thereby operate the sprocket chains. 25

2. An elevator of the character described comprising a supporting frame formed to provide a horizontal portion and a vertical portion, a transverse shaft at the junction of the horizontal and vertical portions forming a pivot therefor, a pair of sprocket wheels mounted upon the shaft, a pair of driving sprocket wheels mounted at the lower end of the vertical portion, a pair of sprocket wheels at the outer end of the horizontal portion, a pair of sprocket wheels inward of said last named sprocket wheels and below the first named pair of sprocket wheels, an endless chain passing over the said sprocket wheels, carriers pivoted upon 30 said chain for movement therewith and including supporting bars extending at an acute angle to the carriers and engaging the chain to support the carriers in an upwardly inclined position when the carriers are moving upward and horizontally, each of said carriers including lateral members and parallel, outwardly projecting tines, side plates mounted upon the vertical and horizontal portions of the supporting frame and between which said carriers move upward and horizontally, corner plates overlapping the horizontal and vertical plates, a hopper discharging between the side plates and having 35 tines projecting into the space between said side plates and spaced intermediate the tines on the carriers, and means for driving said chain. 40

In testimony whereof I affix my signature.
SAMUEL JAMES TRITT.
